UNITED STATES PATENT OFFICE.

MAX VILINSKY, OF SHERBROOKE, QUEBEC, CANADA.

SAFETY GARMENT POCKET.

Application filed March 15, 1920. Serial No. 365,878.

To all whom it may concern:

Be it known that I, MAX VILINSKY, a subject of the King of Great Britain, residing at Sherbrooke, in the Province of 5 Quebec, Canada, have invented certain new and useful Improvements in Safety Garment Pockets; and I do hereby declare that the following is a full, clear, and exact description of the invention, such as will 10 enable others skilled in the art to which it appertains to make and use the same.

The present invention relates to improvements in pockets for garments and more particularly appertains to that class of 15 pockets of the safety or hidden type.

The principal object of the invention is to provide a pocket of the character set forth having a secret compartment therein and which has no departure in appearance 20 from the ordinary pocket.

A further object of the invention is to effectively lock the secret compartment in such manner that the same is not discernible.

With the above and other objects in view 25 which will hereinafter appear as the description continues, the invention consists of the novel features of construction, combination and formation of parts as will be hereinafter more fully described and particularly pointed out in the appended 30 claims.

In the accompanying drawings has been shown a simple and preferred form of the invention, it being, however, understood that 35 no limitation is necessarily made to the precise structural details herein exhibited, but the right is hereby reserved to any changes, alterations or modifications to which recourse may be had that come within the 40 scope of the claims without departing from the spirit of the invention or sacrificing the efficiency of the same.

In the accompanying drawings:

Figure 1 is a detail view with a portion 45 in section of a pair of trousers, illustrating the improved pocket construction;

Figure 2 is a transverse section through the pocket with the safety compartment locked;

50 Figure 3 is a similar view illustrating the ordinary use of the pocket, and

Figure 4 is an illustrative view of the actual positioning of the exterior parts shown in Figure 2.

55 Referring to the figures by numerals of reference, 1 designates the trousers formed

with a side pocket 2. The fabric 4 forming the pockets is stitched at one end, as at 5, to the flap 6, which in turn is stitched to the cloth 7 of the trousers. At the opposite side of the pocket opening a similar flap 8 is stitched at 9 to the cloth 10 and is formed with a button hole 11.

The free end 12 of the fabric 4 at the pocket entrance carries a button 13 on its inner side and the female section 14 of a snap element is sewed to the opposite surface of the free end 12 of the pocket lining. Likewise the female section 15 of the snap element is sewed to the outer surface of the 70 pocket lining. A male section 16 of the snap element is provided upon the flap 6 for engagement with either of the female sections 14, 15.

When it is desired to form the secret 75 pocket as illustrated in Figure 2, button 13 is withdrawn through the button hole 11 in flap 8 and thus the free end of the lining 4 is released. Then flap 6 is lowered and the free end 12 of the pocket lining is inserted thereover. The flap 6 is then folded against the end 12 of the lining and the male section 16 of the snap element is inserted into the female section 14 on the lining.

The pocket assumes its ordinary form, as 80 illustrated in Figure 3, when the free end 12 of the lining is buttoned to the flap 8 of the pocket. In this case, the free end of the flap 6 is secured to the fabric by 90 means of the male section 16, engaging in the female section 15.

In this manner it is obvious that the 95 pocket is formed in such manner as to be provided with a concealed compartment and by the construction of which the ordinary pocket may likewise be formed. This same arrangement may be used in forming pockets of different sizes for different garments.

Having thus full described my invention, what I claim as new and desire to secure by Letters Patent is:—

1. The combination with a garment section having a flap formed thereon adapted 105 to receive a fastener, of a second garment section spaced from the first section, a pocket forming fabric having one end attached to said second section, a male and female clamp member on the contacting 110 surfaces of the second garment section and end respectively, the other end of said fab-

- ric being free and having attached thereto a fastener for coacting with said flap, and having a second female clamp member adapted to engage said male member.
- 5 2. The combination of a garment section having a flap formed thereon adapted to receive a fastener, of a second garment section spaced from the first section, a pocket forming fabric having one end attached to 10 said second section at the outer side thereof, a male and female clamp member on the

contacting surfaces of the second garment section and end respectively, the other end of said fabric being free and having attached thereto on its inner face a fastener 15 for coacting with said flap and having a female clamp member on its outer face adapted to be engaged by said male member.

In witness whereof I have hereunto set my hand.

MAX VILINSKY.
